METHOD OF COATING FLUORESCENT LAMPS

Erwin F. Lowry, Lynn, and Andrew Y. Mace, Marblehead, Mass., assignors to Sylvania Electric Products Inc., Salem, Mass., a corporation of Massachusetts

Application April 30, 1947, Serial No. 744,994

2 Claims. (Cl. 117—33.5)

1

This invention relates to electric lamp coating apparatus and more particularly to apparatus for spraying coating of luminescent material to the inner wall of an elongated glass envelope.

An object of this invention is to provide a method of and apparatus for spraying a suspension of luminescent material on the inner wall of an elongated glass envelope.

Another object of this invention is to provide a method of and apparatus for spraying a suspension of luminescent material on the inner wall of an elongated helical glass envelope from which an electric lamp may be fabricated.

Further objects, advantages and features will be apparent from the following specification when read in conjunction with the accompanying drawings in which:

Figure 1 is a perspective view of the apparatus of our invention.

Figure 2 is an exploded sectional view of a nozzle which we have employed with the apparatus of our invention.

Figure 3 is an enlarged plan view showing how the nozzle is mounted on the spray gun.

In the manufacture of conventional fluorescent lamps of the linear type, the elongated tubular glass envelope is provided with a coating of fluorescent material on the inner wall thereof. This coating is usually applied by flushing the envelope with a body of the fluorescent material. This is accomplished by positioning the elongated tube substantially perpendicular to the horizontal and introducing the body of fluorescent material either from the top or the bottom thereof. In either case the quantity of fluorescent material with which the envelope is flushed is considerably greater than the quantity which actually remains on the wall of the envelope. This excess is permitted to drain from the envelope.

Although the flushing method has proved satisfactory in coating elongated linear glass envelopes, we have found that it leaves much to be desired when the article to be coated is non-linear or curved, such as a helical glass envelope, for example. One of the problems which is presented in trying to flush coat a helical glass envelope is the attainment of a smooth, even coating. When a helical glass envelope is flush coated, the deposited coating, which drains as it dries, follows an irregular and uncontrollable course. This re-

sults in streaky, uneven coating, which is very undesirable. We have, therefore, developed a method of and apparatus for spray coating the wall of the envelope with a suspension of luminescent material.

The apparatus of our invention comprises a drum 1 mounted on a shaft 2 which is supported at its ends by bearings 3 and standards 4 which are mounted on a base 5. Provision is made to 10 slidably mount the drum 1 on the shaft 2 by providing a sliding fit between a keyway 6 in the drum and an elongated key 7 on the shaft. A cam 8 in the form of a single turn helix, the pitch of which corresponds to the pitch of the elongated glass envelope which is to be coated, is mounted on the periphery of the drum adjacent one end thereof. A pair of cam followers 9, which engage the cam 8, are supported in a standard 10. A plurality of spring clips 11, adapted to hold an 15 elongated helical glass envelope 12 are disposed about the periphery of the drum 1 adjacent the other end thereof.

As mentioned above, the apparatus of our invention is designed to permit the envelope 12 to 20 be spray coated with a suspension of luminescent material. A spray gun 13 is employed to apply the coating to the inner wall of the envelope 12. The gun 13 comprises an elongated helical barrel 14, the pitch of which corresponds to the 25 pitch of the envelope 12, and a nozzle 15 disposed at one end of said barrel. The other end of the barrel 14 is connected, through line 16, to a supply of luminescent material suspension. The gun 13 is supported by bracket 17.

In preparing the apparatus of our invention for the spraying operation, the position of the drum 1 is adjusted so that an end of the envelope 12, which is mounted thereon and held by clips 11, is aligned with the nozzle 15 and then the drum 40 1 is rotated to thread the envelope 12 about the gun 13 until the nozzle 15 is disposed adjacent the other end of the envelope. The relative disposition of the envelope 12 and the cam 8 is such that when this operation is performed the cam 8 will 45 be engaged continuously by its followers 9. This arrangement insures the proper threading and withdrawal of the envelope 12 because the path described when the drum is rotated will be the same each time the operation is performed.

The actual spraying operation is performed by

introducing a body of luminescent material suspension under pressure into the gun 13 and causing it to issue from the nozzle 15. While the spray of coating is being deposited on the inner wall of the envelope 12, the drum 1 is rotated in a direction opposite to the direction in which it was rotated to thread the envelope 12 over the gun 13. Thus the envelope 12 is gradually withdrawn from the gun while it is being coated. When the envelope 12 has been rotated to a position where it has been withdrawn from the gun, the flow of fluorescent material suspension from the gun is cut off and the coated envelope is removed from the drum.

The shaft 2 is driven by a motor 18 to which it is connected through a chain 19 and a reduction box 20. The flow of the suspension of fluorescent material from a reservoir 21 to the gun 13 may be controlled by a suitable valve 22. The body of fluorescent material suspension in the reservoir 21 is placed under a pressure of about 70 to 80 pounds per square inch for best results in atomizing the coating material as it is emitted by the nozzle 15. Air under pressure is supplied to the reservoir 21 through line 23.

As mentioned above, the suspension of luminescent material is atomized and sprayed onto the wall of the glass envelope. In changing from conventional flush coating methods to a spraying system we have found that some nozzles of the type employed in flush coating systems do not perform satisfactorily. We have also found that a change was desirable in the fluorescent material suspension.

A spray nozzle of the type which we have found to give very satisfactory results is shown in Figure 2. The nozzle 15 comprises a plug 24, a mixer 25 and a head 26. The mixer 25 is seated in a chamber 27 in the head 26 and the plug 24 is screw-threaded into the end of the head. The plug 24 is provided with an elongated aperture 28 therein which extends from end to end thereof along its longitudinal axis. The plug 24 is provided with a rounded head 29 which fits into a chamber 30 in an end of the mixer 25. The wall of mixer 25 which defines the chamber 30 is provided with two apertures 31 therein. The head 26 is provided with an aperture 32 in the front end thereof.

Figure 3 shows a manner in which the nozzle 15 may be mounted on the end of barrel 14 of the gun 13. We have found it advantageous to use a ball and socket joint in mounting the nozzle on the end of the gun barrel. The nozzle 15 is screwed into a collar 33 on the ball portion of the joint. The ball 34 is seated in a nut 35, which is threaded in an adapter 36 on the end of the barrel 14. The ball 34 is provided with a hole which extends therethrough to permit the flow of fluorescent coating material from the barrel 14 to the nozzle 15.

The coating material as it flows from the barrel 14 through the nozzle 15 passes through the aperture 28 in the plug 24 into the chamber 30 in the mixer 25. The coating material passes out of chamber 30 through apertures 31 therein and flows along the outside wall of the mixer 25 to the head 37 thereof. The head 37 may be undercut to provide a swirling action as the coating material passes through the chamber 27 in the head 26 and into the aperture 32 therein, from which point it is emitted in a spray onto the wall of the glass envelope.

Spraying cannot be done satisfactorily with fluorescent suspensions of the type which has

been employed successfully in flush coating systems because the spray deposition requires special physical properties, such as a very low viscosity and a delicate balance of drying properties to insure sufficiently rapid drying to eliminate the necessity for rotation of the envelope after spraying, yet assure proper leveling to obtain a coating of good appearance and high efficiency.

The fluorescent coating material which we have found to give good results comprises an organic binder material dissolved in a low boiling solvent plus a small percentage of a solvent having a slightly higher boiling point, a plasticizer sufficient to impart desirable properties to the dried binder film, and the finely divided inorganic phosphor which it is desired to add to the tube. Satisfactory coatings have been obtained when the viscosity of this coating suspension is between about 10 to 50 centipoises, as compared to viscosities of the order of 100-400 centipoises which have been used in flush coating systems.

The vehicle comprises about 80.7% of methylene chloride, about 5.3% of methanol, about 5% ethylcellulose and about 9% dimethylphthalate, all percentages being by weight. The viscosity of this vehicle may be adjusted with solvent A which comprises about 90% methylene chloride and about 10% methanol, these percentages being by volume. A concentrated phosphor suspension is then prepared by milling, in a ball mill for example, about 1000 grams of fluorescent powder with about 1700 cc. of the above-mentioned vehicle which has been adjusted to a viscosity of about 42 centipoises with the above-mentioned solvent A. The phosphor suspension from the mill is then adjusted for spraying with solvent B which comprises about 66.7% normal pentane and 33.3% methanol, (the percentages being by volume) until the viscosity of the mixture has been corrected to the 10-50 centipoises range mentioned above. We have found about 22 centipoises to give very good results. A further adjustment is then made with the vehicle mentioned and described above to lower the specific gravity of the mixture to about between 0.980 and 1.000.

What we claim is:

1. The method of spraying a suspension of fluorescent material on the inner wall of an elongated substantially helical glass envelope, said method comprising: threading said envelope over an elongated fixed spray gun; introducing a suspension of fluorescent material into said spray gun and forcing a spray thereof to be emitted by said gun and be deposited on the inner wall of said envelope; gradually withdrawing said envelope as the gun deposits a suspension of fluorescent material on the inner wall thereof; and holding said envelope against relative rotation, with respect to said spray gun in a plane transverse to said spray gun during said withdrawal of said envelope.

2. The method of spraying a suspension of fluorescent material on the inner wall of an elongated substantially helical glass envelope, said method comprising: mounting said envelope on a support; threading said envelope over an elongated fixed spray gun by rotating said support; introducing a suspension of fluorescent material into said spray gun; forcing a spray of said fluorescent material suspension to be emitted by said gun and upon the inner wall of said envelope; rotating said support in a reverse di-

rection from that in which it was rotated when the envelope was threaded over said gun whereby the envelope is gradually withdrawn as it is being sprayed with said suspension of fluorescent material; and holding said envelope against rotation in a plane transverse to said spray gun during said withdrawal of said envelope.
